United States Patent

Des. 236,699
Patented Sept. 9, 1975

236,699

CHALK LINE REEL

Laird Fortune Covey, Easton, Conn., assignor to
The Stanley Works, New Britain, Conn.

Filed Nov. 2, 1973, Ser. No. 412,470

Term of patent 14 years

Int. Cl. D19—06

U.S. Cl. D10—61

FIG. 1

FIG. 4

FIG. 2

FIG. 3

FIG. 5

FIG. 1 is a front elevational view of a chalk line reel showing my new design;

FIG. 2 is a top plan view thereof;

FIG. 3 is a bottom plan view thereof;

FIG. 4 is a left side elevational view thereof; and

FIG. 5 is a rear elevational view thereof shown on a reduced scale.

I claim:

The ornamental design for a chalk line reel, as shown.
